UNITED STATES PATENT OFFICE

166,785

CHILD'S SANDAL OR SIMILAR ARTICLE

Robert T. Wiseman, Canton, Ohio

Application March 22, 1951, Serial No. 14,592

Term of patent 14 years

(Cl. D7—7)

To all whom it may concern:

Be it known that I, Robert T. Wiseman, a citizen of the United States, residing at Canton, in the county of Stark and State of Ohio, have invented a new, original, and ornamental Design for a Child's Sandal or Similar Article, of which the following is a specification, reference being had to the accompanying drawing, forming part thereof, in which:

Figure 1 is a plan view of a child's sandal or similar article showing my new design; and

My design for a child's sandal is characterized by a flat bottomed sole slightly decreasing in thickness near the toe portion which upturns and engages the vamp portion in a manner as shown, in combination with the configuration of the vamp and upper quarter portions, all as illustrated on the drawing.

I claim:

The ornamental design for a child's sandal or similar article, substantially as shown and described.

ROBERT T. WISEMAN.
